UNITED STATES PATENT OFFICE.

MILAN C. BULLOCK, OF CHICAGO, ILLINOIS.

VARIABLE ECCENTRIC FOR STEAM-ENGINES.

SPECIFICATION forming part of Letters Patent No. 274,436, dated March 20, 1883.

Application filed February 19, 1883. (No model.)

To all whom it may concern:

Be it known that I, MILAN C. BULLOCK, a citizen of the United States, residing at Chicago, in the county of Cook and State of Illinois, have invented certain new and useful Improvements in Variable Eccentrics for Steam-Engines; and I do hereby declare the following to be a full, clear, and exact description of the invention, such as will enable others skilled in the art to which it appertains to make and use the same.

The improvement hereinafter described and claimed is part of my invention described in my application for Letters Patent filed June 15, 24, A. D. 1881, and was separated therefrom in compliance with an order of the United States Patent Office, requiring a division of said application.

This part of my invention consists of a variable and reversible eccentric for operating the valve or valves of steam-engines, the distinguishing novel features of which are stated concisely in the claims at the close of this specification.

In order that my invention may be clearly understood, I have illustrated in the annexed drawings, and will proceed to describe, the best form thereof at present known to me.

In the drawings, Figure 1 is a sectional elevation, showing the eccentric and its adjuncts mounted upon the crank-shaft of a steam-engine. Fig. 2 is a perspective view, partly in section, showing a portion of the crank-shaft with the variable eccentric and its shifting mechanism mounted thereon. Fig. 3 is a transverse section, showing the shaft, the ribbed rotating sleeve, the tubular slide and its grooved bush. Fig. 4 is a section showing, in full lines, the eccentric at one limit of its adjustment on the shaft, and in broken lines the opposite limit of adjustment, showing also the link for connecting the eccentric with the ribbed sleeve. Fig. 5 is a sectional view illustrating one method of connecting the eccentric with the ribbed sleeve. Fig. 6 is a sectional view illustrating another method of connecting these parts. Fig. 7 is a perspective view of the spirally-grooved bush.

The same letters of reference are used in all the figures in the designation of identical parts.

The illustrated eccentric A is provided with two straps, so as to adapt it for operating two

valves; but it may be lessened in width and provided with only one strap. The eccentric is pivoted to a wrist-pin, b', projecting from an arm, b, fixed to the crank-shaft B, which passes through a curved slot, a, formed in the eccentric, so that the eccentric may be swung on its pivot b' to adjust it with reference to the crank B' of the shaft B. The curved slot a of the eccentric is so located and proportioned that the engine or engines to which it is applied may be reversed by swinging the eccentric from one extreme position to the opposite one. By lesser adjustments of the eccentric the throw of the valves may be readily adjusted. The eccentric A, thus pivoted, is connected by a link, a', to an arm on the adjacent end of a sleeve, C, which is so fitted upon the crank-shaft that it may be rotated, but cannot be moved endwise thereon; or, instead of connecting the eccentric and rotating sleeve by means of the link a', gear-teeth may be formed at the end of said sleeve to engage a segmental rack formed on or connected to the face of the eccentric, as shown in Fig. 6. This sleeve C is constructed with spiral ribs or threads c on its surface, and is encircled by a bush, D', in which spiral grooves d' are cut to engage the spiral threads on the sleeve. It is apparent that this construction may be modified by forming the grooves in the sleeve C and providing the bush D' with spiral ribs or threads; or one of the members C or D' may be provided with pins or studs, either fixed or removable, to engage the spiral grooves of the other member. The bush D' is fixed in the split end of a tubular slide, D, so as to form part thereof; but the bush may be dispensed with, and the tubular slide may itself be provided with either grooves or ribs to engage the grooves or ribs of the rotating sleeve C. The other and contracted end of the tubular slide is connected by feather and groove to the crank-shaft, with which it turns, but on which it may be slid endwise. Thus the bushed tubular slide will firmly hold the rotating sleeve, and through it the eccentric. It will be observed, however, that by sliding the tubular slide on the crank-shaft its spirally-grooved bush will turn the spirally-threaded sleeve, which will in turn, through the medium of its connection with the eccentric, swing the latter on its pivot. The tubular slide is encircled at its contracted end by

a ring, D^2 , studs on which are engaged by the shifting or reversing lever E , by operating which the eccentric may be adjusted at pleasure. The split end of the tubular slide is constructed with ears, so that the segments may be drawn together by bolts d , as shown in Figs. 2 and 3, and lost motion between the spiral threads and spiral grooves be readily taken up. The slot a of the eccentric is of sufficient width to permit the eccentric to move freely, but not loosely, back and forth upon the crank-shaft, and it may have continuous walls, or be provided with offsets, so that it will move more freely upon the shaft when being shifted. The bush D' , when used, is secured to the tubular slide by any suitable means—such, for instance, as the screws d^2 , shown in Fig. 3.

What I claim as my invention, and desire to secure by Letters Patent, is—

1. The combination, substantially as before set forth, of the slotted eccentric pivoted to an arm on the crank-shaft, the sleeve mounted to rotate on the crank-shaft for shifting the eccentric across the axis thereof, and the tubu-

lar slide feathered to the shaft and adapted to rotate the sleeve thereon.

2. The combination, substantially as before set forth, of the slotted eccentric pivoted to an arm on the crank-shaft, the sleeve linked to said eccentric, and means for rotating said sleeve.

3. The combination, substantially as before set forth, of the slotted eccentric pivoted to an arm on the crank-shaft, the spirally-threaded sleeve linked to said eccentric, and the tubular slide having grooves to engage the spiral threads of the sleeve.

4. The combination, substantially as before set forth, of the slotted eccentric pivoted to an arm on the crank-shaft, the spirally-threaded sleeve linked to said eccentric, and the adjustable tubular slide the spirally-grooved bush of which engages the spirally-threaded sleeve.

In testimony whereof I affix my signature in presence of two witnesses.

MILAN C. BULLOCK.
